(57) CLAIM

The ornamental design for a food blend product, as shown and described.

DESCRIPTION

FIG. 1 is a perspective view of a food blend product showing my new design;

FIG. 2 is a perspective view of the first of two pieces comprising the food blend product, shown separately for clarity of disclosure;

FIG. 3 is a right side elevational view thereof, the left side being a mirror image;

FIG. 4 is a top plan view thereof, the bottom being a mirror image;

FIG. 5 is a front elevational view thereof, the rear being a mirror image;

FIG. 6 is a perspective view of the second of two pieces comprising the food blend product, shown separately for clarity of disclosure;

FIG. 7 is a right side elevational view thereof, the left side being a mirror image;

FIG. 8 is a top plan view thereof, the bottom plan being a mirror image; and,

FIG. 9 is a front elevational view thereof, the rear being a mirror image.
